US00D995219S

(12) **United States Design Patent** (10) **Patent No.:** **US D995,219 S**
Warr (45) **Date of Patent:** **** Aug. 15, 2023**

(54) **CHILDREN'S PLATE**

(71) Applicant: **Garret M Warr**, Hope Valley, RI (US)

(72) Inventor: **Garret M Warr**, Hope Valley, RI (US)

(**) Term: **15 Years**

(21) Appl. No.: **29/788,358**

(22) Filed: **May 9, 2021**

(51) **LOC (14) Cl.** **07-01**

(52) **U.S. Cl.**

USPC **D7/587**
